PHONOGRAPH PICK UP

William H. Hutter, Racine, Wis., assignor to
Webster Electric Company, Racine, Wis., a
corporation of Wisconsin

Application October 13, 1930. Serial No. 488,243

8 Claims. (Cl. 179—100.41)

This invention relates in general to reproducing devices or phonographs and has more particular reference to a phonograph pickup for translating mechanical movements into electrical impulses

5 which may subsequently be reproduced by the phonograph.

A primary object of the invention is the provision of an improved phonograph pickup or translating device for use in sound reproducing devices 10 or phonographs.

10 An important object of the invention is the provision of such a phonograph pickup or translating device including a generating assembly having an adjustable gap between the pole pieces and 15 the armature.

Another important object of the present invention is the provision of a novel phonograph pickup having a vibratory member so pivoted between magnetic pole pieces that the movement of said 20 member is accurately and efficiently converted into correlative electrical impulses.

An important object of the present invention is the provision of such a phonograph pickup or translating device which includes a generating 25 assembly, the magnetic and electrical members of which are so designed and assembled that the mean magnetic path will be of minimum length.

30 A further important object of the present invention is the provision of a yoke assembly for electrical phonograph pickups which is provided with pole pieces of such shape as to provide a fulcrum for cam levers movably secured to the pole pieces and adapted to adjust resilient members carried by the pole pieces whereby to adjust the pressure 35 on the armature arranged between said pole pieces.

Other objects and advantages will appear more fully from the following description and from the accompanying drawings, in which similar characters 40 of reference indicate similar parts throughout the several views.

In the drawings:

Fig. 1 is a side view of a phonograph pickup or translating device embodying features of the invention;

Fig. 2 is a front elevation of the phonograph pickup shown in Fig. 1, with parts broken away;

Fig. 3 is a longitudinal section taken substantially on the line 3—3 of Fig. 2;

Fig. 4 is a horizontal section taken substantially on the line 4—4 of Fig. 3;

Fig. 5 is a section taken substantially on the line 5—5 of Fig. 3;

Fig. 6 is a section taken substantially on the line 6—6 of Fig. 4;

Fig. 7 is an enlarged perspective view of a lever member for adjusting the pressure on the armature of the phonograph pickup shown in Fig. 1;

Fig. 8 is an enlarged perspective view of a portion of the yoke employed in the translating device of the invention and shows certain assembly details;

Fig. 9 is an enlarged perspective view of the vibratory member employed in the translating device of the invention;

Fig. 10 is a perspective view of a portion of the yoke employed to bridge the magnet of the novel phonograph pickup, and

Fig. 11 is a perspective view of a resilient member used to mount the armature of Fig. 9.

The present invention contemplates briefly an improved translating device or phonograph pickup of the electro-magnetic type which is provided with a yoke surrounding and carrying a generator coil and extending between or bridging the poles of a magnet. This yoke comprises pole pieces carrying non-magnetic members for adjustably spacing the pole pieces and for providing a pivotal mounting for a vibratory member or 75 armature extending through the coil to vary the gap between the pole pieces at the opposite sides of the coil, the pivotal axis of the armature being between the two gaps at the opposite ends of the coil.

This vibratory member or armature is actuated by the stylus or needle of the phonograph in playing a record and reciprocates between the pole pieces at the opposite sides of the coil. This vibration or reciprocation of the armature varies 90 the reluctance of the magnetic circuit which induces a current in the generator coil correlated to the mechanical movements of the needle or stylus produced by the record. These variations in current may be amplified and converted into 95 sound waves in a well known manner.

To accomplish the foregoing objects a casing 100 15 comprising a base or mounting plate 16 and a cover member 17 is secured at an end of a tubular arm or tone arm 18 by means of mounting screws 19 and encloses a generating assembly, generally designated by the reference character 21. The casing may be made of any suitable non-magnetic material such as aluminum.

The generating assembly 21 includes a U-shaped 105 magnet 22, preferably of the permanent magnet type mounted on the base plate 16 by means of a strap or tie plate 23 and a screw 24 threading into the plate 16. The strap 23 is provided with a finger or projection 23' into which a cover re- 110

taining screw 25 threads to hold the cover member 17 to the plate 16. A magnetic yoke generally designated by the reference numeral 26 surrounding a generating coil 27 provides with the 5 coil a unitary assembly extending or bridging between the poles of the magnet 22. This unitary assembly is secured to the base plate 16 by means of through bolts or studs 28 and nuts 29 arranged at each end of the yoke 26 to hold it 10 adjacent the poles of the magnet.

The coil 27 is illustrated, particularly in Figs. 1 and 5, as being of greater diameter than the width of the yoke 26 and extends beyond the yoke laterally into a recess 31 provided in the base 15 plate 16 for that purpose. A terminal block or strip 32 is mounted on a stud 33 integral with the base plate 16 by means of a screw 34 and carries a plurality of terminals 35 connected to the coil 27 by conductors 36. The terminals 35 may 20 be connected by conductors 37 in the tubular arm 18 to a suitable amplifying device the output of which is converted into sound waves.

The magnetic yoke 26 is constructed and assembled as shown in Figs. 5 and 8 to provide 25 magnetic pole pieces 38 and 39 which are substantially U-shaped to accommodate the coil 27 and to provide a mean magnetic path of minimum length. The pole piece 38 comprises a side member 41 spaced apart from a side member 42, the side members 41 and 42 being connected by an integral end piece 43 to provide a short magnetic path between the side members which extend therefrom at a pole of the magnet 22 to substantially centrally of the coil 27, the 30 side members 41 and 42 being reduced in width to provide pole tips 44 and 45 respectively at opposite ends of the coil, and a shoulder 46. In like manner the pole piece 39 is provided with side members 47 and 48 and an integral end piece 49. These side members are constructed 35 with pole tips 51 and 52 and shoulder 53 respectively corresponding to the pole tips 44 and 45 and the shoulder 46.

Non-magnetic members 54, shown more particularly in Figs. 8 and 10 of any suitable shape such as channel-shaped, are formed with spaced sides 55 which are receivable in aligned slots 56 in opposite sides of the pole pieces 38 and 39 to hold the pole pieces in such an adjustable position as to provide a small adjustable space or gap between pole tips 44 and 51 and a larger adjustable gap or space between pole tips 45 and 52. The screws 28, passing through aligned slots 57 at each end of each member 54 and the holes 58 and 59 in the pole pieces 38 and 39 respectively hold the yoke assembly in assembled relation adjacent the poles of the magnet 22. The slots 57 at the ends of the non-magnetic members 54 extend longitudinally of the members 54 and permit adjustment of the pole pieces to vary the distance or gap between pole tips 44 and 51 and the gap between pole tips 45 and 52 to adapt the generating unit to various magnetic and playing conditions.

The face of each channel member 54 is cut away or apertured as at 61 to accommodate the coil 27 having a larger diameter than the width of the pole pieces. These channel members serve as a mounting for a vibratory member or armature 62, see Fig. 9, having a plurality of knife edges 63 which engage in corresponding grooves 64 of the channel members 54. The knife edges 63 are held in the grooves 64 by a resilient strip or spring 65 having a knife edge 66 which engages a side 67 of an aperture 68 in the armature 65, the side 67 and knife edge 66 being in alignment with the knife edges 63 so that the armature may pivot about the knife edges with a minimum of friction. This spring 65 is adjustably positioned in aligned grooves or slots 69 in the side members 42 and 48 of the pole pieces and is adjustably held therein by screws 71 and longitudinal end slots 71' to form an efficient pivotal mounting for the armature between the gaps formed by the pole tips 44 and 51 and pole tips 45 and 52 and to permit the adjustment of the pole pieces 38 and 39. The coil has its end 72 grooved as at 73 to accommodate the grooved portions of channel members 54 for this purpose.

At one end of the armature 62, a rectangular projection or lug 74 extends beyond the sides of the pole pieces 38 and 39 and is provided with a bushing 75 to separate the armature from the cover member 17. This projection registers with a slot or opening 76 in the cover member through which a needle or stylus 77, held therein by a retaining screw 78, projects for engaging and playing a record. This end of the armature substantially fills the larger gap between the pole tips 45 and 52. The other end of the armature is reduced in thickness as at 79 and is adapted to reciprocate between pole tips 44 and 51 as the armature vibrates or reciprocates about its pivot.

The grooves 64 in the channel members 54 are located midway between the pole pieces 38 and 39 and have a depth sufficient to establish the axis of the pivot of the armature between the gaps formed by the pairs of spaced pole tips. This arrangement of the armature pivot between the air gaps and the construction of pole pieces 38 and 39 to provide short magnetic paths between the poles of the magnet add greatly to the sensitivity of the generating assembly because the position of each end of the armature with respect to the pole tips affects the magnetic flux impressed into the armature by the magnet.

The reluctance of the air gaps between the reduced end of the armature and the pole tips 44 and 51 and between the opposite end of the armature and the pole tips 45 and 52 will vary as the armature vibrates. As the end 79 of the armature approaches nearer the pole tip 44, the reluctance through this pole tip, armature 62, 125 and the pole tip 52 will be decreased and the reluctance through the pole tip 45, armature 62, and the pole tip 51, will increase, thereby permitting the magneto-motive force of the magnet to impress a flux upwardly through the armature as viewed in Fig. 5. A flux having a direction downwardly through the armature is set up in the magnetic circuit as the armature moves in the opposite direction. This vibration of the armature produces a corresponding variation in 135 the flux in the armature, which induces a current in the coil 27, the wave form of which bears a definite relation to the vibrations of the armature or the needle 77 carried thereby.

Thus pole pieces 38 and 39, the coil 27, and the armature 62 are assembled as a unit by means of the channel shaped members 54 and the resilient member 65 which pivotally support the armature on an axis between the gaps formed by the pole pieces. This unit may be mounted 145 on the plate 16 by the studs 28 and the nuts 29 for testing and removed for adjustment of the gaps between the pole tips and the armature. These gaps between the pole tips and the armature at opposite ends of the coil 27 are adjust- 150

able by loosening the screws 71 in the slots 71 of the resilient member 65 and sliding the pole pieces along the channel sides 55 engaging in the slots 56 of the pole pieces. When the gaps 5 have been adjusted to suit the magnetic circuit and to provide a desired tone or to suit any desired magnetic or playing condition the screws 71 may be tightened and the unit again mounted on the plate 16 by the studs 28 and the nuts 29.

10 The knife edge support for the armature 62 makes an efficient damping means possible for the armature and thereby permits the use of the resilient member to provide a yieldable and substantially motionless bearing for the armature of this novel adjustable unit or yoke. This damping of the armature 62 is accomplished by resilient material 82 in slots 81 which are formed in the adjacent ends of the pole tips 44 and 51 by a round tool to provide a circular section whereby to prevent the resilient material 82 from working out sidewise. This resilient material 82 engages the free end 79 of the armature to maintain the armature in the normal position centrally of the gap between the pole tips 44 and 51.

Each side member 41 and 47 carries a lever 83, see Fig. 7, having a handle 84 accessible when the cover member 17 is removed to adjust the pressure exerted against the armature by the resilient material 82. These levers 83 are carried on the pole pieces 38 and 39 by mounting screws 85 engaged by cam slots 86 for guiding a depending finger or lug 87 extending into each slot 81 for engagement with the resilient material 82, to vary the pressure exerted thereby against the end 79 of the armature. The movement of the lever 83 is accomplished about a depending lug 88 fulcruming against the shoulders 46 and 53.

46 The pole tips 44 and 51 attract the armature in accordance with its proximity to a pole tip, but the resilient material 82 applies a force tending to return the armature 62 to its central position, which also increases with the proximity 45 of the armature to a pole tip so that the magnetic attraction of the armature is counterbalanced by the resilient material and therefore will not effect the movement of the armature.

In operation the stylus or needle is vibrated in 50 playing a record. This vibration of the stylus is transferred or communicated to the armature 62, causing the reduced end 79 to reciprocate between the pole tips 44 and 51 and the other end of the armature to reciprocate between pole tips 45 and 52. The magnet 22 sets up a magneto-motive force between the pole pieces 38 and 39. The flux produced by this magneto-motive force is reversed in direction each time the reduced end 79 of the armature passes its 55 central position, thereby inducing a current in the coil 27, correlated to the movement of the armature 62 or the needle 77 carried thereby. This current may then be amplified and converted into sound by any suitable means.

35 A feature of the present invention is the adjustable air gaps between the pairs of pole tips whereby to vary the reluctance of the magnetic circuits for magnets having variable or different magneto-motive forces, and for amplifiers or 40 phonographs having different characteristics.

While I have illustrated and described a specific embodiment of my invention, many modifications may be made without departing from the spirit of the invention, and I do not wish to be limited to the precise details set forth but

desire to avail myself of all changes within the scope of the appended claims.

Having thus described my invention, what I claim is new and desire to secure by Letters Patent of the United States is:

80 1. A phonograph pickup comprising a magnet having adjustably spaced pole pieces provided with corresponding slots extending longitudinally of said pole pieces, a coil carried by said pole pieces, a movable armature passing through said coil and between said pole pieces, and a mounting means for said armature carried in said corresponding slots.

85 2. A phonograph pickup comprising a magnet having adjacently disposed pole pieces provided with corresponding slots at opposite sides of said pole pieces, a coil carried by said pole pieces, non-magnetic members slidably arranged in said slots and bridging between said pole pieces, and a movable armature between said pole pieces pivotally engaging said members at one side of said coil, and having a portion extending through said coil whereby to provide unequal variations in the magnetic reluctance between said armature and said pole pieces at opposite sides of said coil.

90 3. A phonograph pickup comprising a magnet, adjustable pole pieces therefor having aligned slots, channel members engaging in said slots and maintaining said pole pieces in adjustable spaced relation, a coil between said spaced pole pieces, and an armature between said pole pieces pivotally engaging said channel members at one side of said coil and having a portion extending therethrough and an oppositely disposed portion 105 extending beyond said pole pieces for actuating the first said portion between said pole pieces.

100 4. A phonograph pickup comprising a magnet, a coil, a yoke bridging the ends of the magnet and surrounding the coil, said yoke including a pair 115 of adjustable pole pieces having a plurality of aligned slots, and a plurality of non-magnetic members engaging in said slots and holding the ends of said pole pieces in spaced relation, and a vibratory armature pivotally mounted on the 120 non-magnetic members inwardly of the surface of the pole pieces on one side of said coil and extending into the gap between the pole pieces on the other side of said coil whereby to induce a current in said coil.

125 5. A phonograph pickup comprising a coil, a yoke for the coil including a plurality of non-magnetic members having aligned grooves in corresponding sides, a pair of U-shaped magnetic members having aligned slots carrying said non-magnetic members, said magnetic members being held in adjustable spaced relation thereby and extending from centrally of the coil over the lateral sides of said coil to centrally of the other side of said coil, and providing adjustable gaps 130 between the ends of said magnetic members, and an armature having a knife edge support carried in the aligned grooves of said non-magnetic members between said gaps, said armature extending through said coil and having its ends 140 reciprocable in said gaps.

135 6. A phonograph pickup comprising a coil, a pair of pole pieces at each end of said coil having gaps therebetween, a magnet associated with said pole pieces, an armature extending through 145 the gaps between the pole pieces and having a plurality of knife edges a plurality of channel members having grooves therein carrying said armature and said pole pieces, the pivot point of said armature being between the pairs of pole 150

pieces at the end of said coil, said pole pieces being adjustable with respect to said channel members to adjust the gap between said pole pieces, and means for moving the armature about its 5 pivot to generate a current in said coil.

7. A phonograph pickup comprising a magnet and a unitary generating assembly bridging between the poles of said magnet and including a coil, complementary bifurcated pole pieces adjustably assembled about said coil and a damped 10 vibratory member having a pivotal mount-

ing intermediate the furcations of said bifurcated pole pieces.

8. A phonograph pickup comprising the combination of a magnet with a unitary generating assembly having adjustably spaced pole pieces, a vibratory member between said pole pieces, and non-magnetic assembly means holding said pole pieces in adjusted relation with respect to said vibratory member. 80

WILLIAM H. HUTTER.
